MOTOR COACH

Roland E. Gegoux, Pontiac, Mich., assignor to General
Motors Corporation, Detroit, Mich., a corporation of
Delaware

Filed May 16, 1960, Ser. No. 60,613

Term of patent 7 years

(Cl. D14—3)

Figure 1 is a side elevational view of one side of a motor coach embodying my new design;

Figure 2 is a top plan view;

Figure 3 is a view of the opposite side;

Figure 4 is a front elevational view, and

Figure 5 is a rear elevational view.

The dominant features of my new design reside in the full line portions of the drawings.

I claim:

The ornamental design for a motor coach, substantially as shown and described.
